UNITED STATES PATENT OFFICE.

ROBERT RUDLAND BODE, OF HONOLULU, TERRITORY OF HAWAII.

REPAIR ATTACHMENT FOR PIANO HAMMER HEADS.

Application filed June 22, 1928. Serial No. 117,733.

The piano hammer heads to which this attachment is applicable are formed with an impact member composed of thick felt; and under continued usage, such felt becomes compressed and hardened where it strikes upon the piano wire so that the tones of the piano are metallic and out of tune.

In my former Letters-Patent, No. 888,141, patented May 19, 1908, and No. 934,654, patented September 21, 1909, I have set forth means adapted to restore the quality of the hammer by applying a strip of soft material to that surface of the felt head which strikes the piano wire, showing a stirrup of thin wire having sharp pointed fingers to enter the felt and secured to the strip by a loop like sheet metal body having detents that were inserted through the strip and bent over thereonto.

The present invention is an improvement upon the devices shown in both of said patents, and has for its object, the avoidance of difficulties long experienced without any remedy known to me or others so far as I am aware and which have prevented me from successfully marketing the patented inventions.

I have found that serious difficulty arose with respect to the attachment shown in my Patent No. 934,654, in addition to the liabilities of slipping and loosening, mentioned in said patent, and that such difficulty arose from several sources, viz—

I have found in actual practice that the connection between the strip and the felt of the hammer head was cumbersome and likely to pull the material so as to allow the loops to move apart from each other, thus loosening the strip; and also that the points of the fingers were likely to come loose from the felt of the hammer head so that the strips in some instances would become detached, thus requiring renewed attention.

Furthermore it was difficult to tightly assemble the stirrups, loops and strip quickly and fasten them tightly together.

An object of the present invention is to overcome those difficulties and objections, and to cheapen and strengthen the attachment, facilitate assembly, and to guard against any tendency to loosen or become detached.

Another object is to produce the attach-

ment in a cheap and convenient way without special tools, and this I accomplish in the manner hereinafter set forth.

Other objects, advantages and features of invention may appear from the accompanying drawing, the subjoined detailed description and the appended claims.

The accompanying drawing illustrates the invention.

Figure 1 is a face view of the improved attachment on an enlarged scale.

Fig. 2 is a longitudinal section on line x^2-x^4 , Fig. 1.

Fig. 3 is a broken perspective view on a somewhat smaller scale, of a piano hammer with my attachment applied thereto.

Fig. 4 is an enlarged fragmental section on said line x^2-x^4 , Fig. 1.

Fig. 5 is a view of a stamping ready to be bent onto one end of the strip.

Fig. 6 is a fragmental view illustrating the strip and eyelet mechanism of a form for riveting the clasp onto the strip.

1 indicates the renewing strip which is preferably of felt of elongate rectangular form. 2, 3, 4 indicate members or parts of spring wire stirrups, the member 2 being straight, the side members 3 being at right angles thereto and the inwardly extending return hooks 4 being bent slightly toward the member 2. 5 indicates a folded sheet metal clasp embracing the member 2 and the end of the rectangular strip 1 fixed to said rectangular strip by a riveted eyelet 6. Each end of the strip 1 is fitted with the clasp, stirrup and eyelet.

The sheet metal of which the clasp is formed may be thin sheet brass either spring brass or soft brass and in practical manufacture the blanks such as shown in Fig. 5 will be bent into form for folding about the ends of the renewal strip 1 and then will be placed on the intermediate member of the stirrup and put in position with such member against the end of the strip and then the folds of the clasp will be punched and eyeleted at a single operation by an ordinary eyeleting machine, which may be of the common hand type, thus completing the attachment in well finished form.

In practice to apply the attachment to the felt portion of the hammer head 7, the strip 1 will be brought into the appropriate

position and the spring wire stirrups will be fixed by drawing the strip tightly over the felt head and compressing the felt, the hook terminals being spread apart to allow 5 the rearwardly turned hooks to be inserted into the compressed felt until the side arms 3 come into normal position against the side of the felt head with the tension of the felt acting to further seat the curved hooks and 10 to prevent the escape of the same under any condition except the reversal of the operation by which they were seated.

In this manner the strip is held perfectly true and taut and the hooks cannot come 15 loose by use of the piano.

The clasps are shown provided with rounded tips and the eyelet is centrally located with respect to said tips and the head 8 and burr 9 of the eyelet practically rivet 20 the two trunks of the clasp tightly onto the strip.

It is understood that the strip and accompanying parts may be of any size, thickness and weight within the judgment of the 25 manufacturer and a feature of the invention is the construction which allows the device to be applied in a very light form and with great economy of time and material.

The felt strip may be about $\frac{1}{32}$ inch thick 30 more or less and the clasps may be sheet brass of 26 gage, more or less, and the eyelets may have a bore of about $\frac{1}{16}$ of an inch diameter, more or less.

In Fig. 6, 10 indicates the anvil of a well 35 known riveting machine, 11 the rivet holder in its elevated rivet holding position, 12 is the hollow presser foot adapted when down to compress the clasp and strip toward the head 13 of the hollow rivet. 14 is the rivet 40 setting die that operates in said machine in conjunction with the presser foot 12 to crush the hollow rivet down into the position indicated in dotted lines at 15.

In practice the rivet may be applied with 45 either form of well known riveting devices, the hole in the clasp and in the strip being cut simultaneously with the insertion of the rivet through the brass and the strip.

The strips may be made in quantity production and may be sold to the piano tuner 50 in sets and by him applied, or they may be applied by any skillful workman.

By providing a clasp blank 5 with rounded ends and securing it in place by the hollow rivet, lightness, strength and compactness are secured in a manner I have heretofore been unable to attain.

The blank 5 is of oblong, preferably elliptic form and the rivet is applied to pierce 60 the ends of the clasp practically central to the arcs 16 at the ends of the blank as indicated in Fig. 3 and by dotted lines at 17 in Fig. 5.

In Fig. 6 it is understood that the punchings of the brass and the strip have been

displaced after the punching and therefore are not shown in the drawing.

The closed head of the eyelet may be punched out by a second operation of the presser foot and reciprocation upward of 70 the punch 1, which thus removes the metal portion of the rivet shown in broken lines across the punch at 15, in Fig. 6.

The provision of a securing means, such as the hollow rivet, made as an element distinct from the clasp, allows the employment of relatively light weight material in the clasp body and the hollow rivet provides a relatively large areal contact, or grip, with the felt strips, and thus the tendency of 80 "stretching" in the felt, at such points of connection, is minimized, and loosening of the strip over the hammer head is largely obviated.

The "pointed fingers", or hammer head 85 engaging points, which are curved in their lengths, or formed as "hooks" bent toward the intermediate member of the stirrup, by reason of their re-entering angle with respect to the hammer head overcomes their 90 tendency to move laterally, or back out, from their seated positions.

The device, as a whole, is of such inconsequential weight as to have minimum effect 95 upon the "balance" of the hammer action.

I claim:

1. The improved repair attachment for piano hammer heads set forth, comprising in combination a renewal strip, of stirrups each having an intermediate member and 100 fingers the ends of which form sharp hooks bent inwardly and curved toward such intermediate member; said intermediate members being against the ends of the strip; clasps of thin sheet metal bent upon the 105 intermediate members and over the ends of the strip and holding the intermediate members in position, and hollow rivets extending through the clasps and the strip at the ends of said strip respectively and rigidly 110 and permanently securing said clasps onto said strip.

2. The combination with a repair strip, of stirrups having intermediate members fastened to the ends of the repair strip and 115 having fingers provided with hooks that are bent inwardly and toward the intermediate members of the stirrups.

3. The means for fastening a stirrup to a repair strip for hammer heads which consists in a clasp of thin sheet metal embracing 120 the end of the strip and a member of the stirrup and a hollow rivet secured through the strip and the ends of the clasp.

4. A repair attachment for piano hammer heads, comprising a strip of felt, a clasp of oblong shape, having rounded tips and formed of thin, light weight sheet material, doubled to embrace the end of the strip of felt, a hollow rivet extended through the 125 130

felt and through the doubled clasp centrally of its rounded tips, a stirrup, having a straight member embraced in the doubled end of the clasp, a pair of side members 5 extending substantially at right angles to said straight member and an inwardly extending return hook, bent toward said

straight member, at the end of each side member.

In testimony whereof, I have hereunto 10 set my hand at Honolulu, Territory of Hawaii, this 7th day of June, 1926.

ROBERT RUDLAND BODE.
